UNITED STATES PATENT OFFICE.

LEROY D. KELLOGG, OF CHICAGO, ILLINOIS, ASSIGNOR TO KELLOGG SWITCHBOARD AND SUPPLY COMPANY, OF CHICAGO, ILLINOIS, A CORPORATION OF ILLINOIS.

TELEPHONE SYSTEM.

Application filed January 4, 1919. Serial No. 269,578.

To all whom it may concern:

Be it known that I, LEROY D. KELLOGG, a citizen of the United States of America, residing in Chicago, county of Cook, and State of Illinois, have invented certain new and useful Improvements in Telephone Systems, of which the following is a specification.

My invention relates to telephone systems in which automatic switches are employed, for completing connections between subscribers' lines, of the type which have bank contacts divided into groups, and co-operating movable contact makers adapted to receive a primary adjustment to select a group of contacts and thereafter, a secondary adjustment to select a contact in the elected group. My invention has to do more particularly with the mechanical construction of the above-mentioned type of switches, and with the circuit arrangements adapted for use with the switches.

Prior to my invention systems of the so-called two-wire type, in which the switches are controlled over the two sides of a circuit in series, have been provided with slow-acting relays or specially constructed and adjusted relays to secure the necessary circuit changes in systems of this character.

It is an object of my invention to produce a system of the so-called two-wire type in which all of the switch relays are of the ordinary type and are not slow acting or specially constructed and adjusted to secure the necessary circuit changes to operate switches of the two-dimension type over the two sides of a circuit in series.

A further object of my invention is the production of a switch structure which is provided with an operating magnet that moves the carriage of the switch in one direction for both the group selecting operation and for the contact selecting operation in the elected group.

It is a further object of my invention to so arrange the switch structure that the one motor magnet not only advances the switch carriage, but also returns the same to normal position.

Further objects of my invention reside in the means provided to advance and return the switch, the novel manner in which the switch operates to select an elected group of contacts, and the unique method in which

the different circuit changes are brought about.

A further object of my invention is to produce an improved switch structure and co-operating circuit which embody desirable features and advantages all in a simple, efficient and economical manner, which is most efficient and economical in its operation, and which has its parts so constructed and combined as to make them readily accessible for repair and adjustment.

Other features of my invention will be more particularly pointed out in the following specification and in the appended claims.

For a more complete understanding of my invention, reference may be had to the accompanying drawings in which like reference characters denote like parts in the different views, and in which:

Fig. 1 is a front elevation of the switch structure of my invention;

Fig. 2 is a plan view of Fig. 1;

Fig. 3 is a bottom view of Fig. 1;

Fig. 4 is a sectional view along the line 4—4 of Fig. 1;

Fig. 5 is a side elevation of a modified form of driving mechanism for the switch as illustrated in Figs. 1 to 4;

Fig. 6 is a plan view of Fig. 5;

Fig. 7 is a side elevation of a circuit changing switch which operates in connection with the driving mechanism of Fig. 6;

Fig. 8 is a plan view of Fig. 7;

Fig. 9 is a side elevation of a connector switch structure;

Fig. 10 diagrammatically shows a group selecting switch, and

Fig. 11, which comprises parts 1, 2 and 3, is a diagrammatic illustration of the circuit adapted to be used in connection with the switch structures of my invention.

The apparatus illustrated in Figs. 1 to 10, inclusive, is the mechanical switch apparatus and its associated mechanism for use in connection with the circuits shown in Fig. 11, parts 1, 2, and 3. Referring first to the switch structure illustrated in Figs. 1 to 4, inclusive, in which the preferred form of the selector switch is shown, it comprises in general a suitably supported carriage C slidably mounted and which is adapted to be moved in a horizontal direction by means of a motor magnet MM. A secondary carriage

SC is suitably supported by a frame which is in turn supported by the main carriage C. The secondary carriage SC carries a relay TWR which is supplied with a wiper carrying arm WA which arm supports the wipers W and the group wiper GW. A bank of contacts B suitably supported is operatively associated with the wipers W and a set of group contacts GC is operatively associated with the group wiper GW.

Referring now more in detail to the switch structure as illustrated, it comprises a carriage C slidably supported upon rods 2 and 3, which rods pass through suitable openings in the carriage C. The rods 2 and 3 are supported by end plates 4 and 5, the said end plates 4 and 5 being provided with suitable angular portions 4' and 5' by which the end plates 4 and 5 are secured to a base 6. A motor magnet MM is provided for moving the carriage C and comprises a heel iron 7, armature 8, and an electromagnet 9, the said motor magnet MM as a unit being suitably secured to a bracket 10 which bracket 10 is in turn secured to the base 6. A set of interrupter springs 73 and 74 are operatively associated with the armature 8 and are mounted upon the heel iron 7 but insulated therefrom. Racks 11 and 12 are supported on the carriage C by means of yoke pieces 13 and 14, which yokes are secured to the carriage C by means of screws 15. The racks 11 and 12 are slidably supported in the yokes 13 and 14 and they are provided with a plurality of teeth which are for co-operation with the pawls 16 and 17, respectively, to move the carriage C in two directions. The said pawls 16 and 17 are pivotally supported by the armature 8 of the motor magnet MM. The successive energizations of the motor magnet MM, as will be more fully hereinafter described, cause the pawl 16 to engage successive teeth of the rack 11, thereby moving the carriage C in a horizontal direction. The selector switch of my invention is adapted to take twenty-two steps and upon the twenty-second step, the carriage C is in its foremost position. When the magnet MM causes the carriage to take its twenty-second step, the plate 18 secured to the rack 12, which is provided with a cam edge 19, engages a rod 20, which rod 20 is suitably secured to the base 6, and as the racks 11 and 12 are slidably supported by means of the yokes 13 and 14, the rack 11 is moved until the teeth of the same are out of engagement with the pawl 16 and the rack 12 is moved in the position occupied by the rack 11, so that the teeth of the rack 12 are operatively associated with the pawl 17, so that the carriage may be stepped back to normal by the motor magnet MM, as will be more fully hereinafter described. When the carriage C is being restored and upon the twenty-second return step a plate 21, similar to that

of 18 and suitably secured to the rack 11 and also provided with a cam edge 22, engages a rod 23 which causes the racks 11 and 12 to be moved in the direction opposite to that upon the forward motion of the carriage C until the pawl 17 is free of the teeth of the rack 12 and the teeth of the rack 11 are again in operative relation with the pawl 16, so that the carriage may again be stepped in a forward direction. To keep the racks 11 and 12 in their different positions, I provide a spring 24 suitably secured to the carriage C, as clearly illustrated in Fig. 4. Notches 25 are provided in the racks 11 and 12 which are engaged by the spring 24 depending upon the positions of the racks 11 and 12. The spring 24 and notches 25 are so arranged that when the racks 11 and 12 start to move from one position to the other, the said spring and notches co-operate to snap or assist the racks into position. A rack 26 is suitably secured to the side of the carriage C by means of screws 27 and is provided with a plurality of notches which are successively engaged by a spring 28 to hold the said carriage C in its different positions when being advanced step by step by the energizations of the motor magnet MM. The spring 28 is secured to a suitable bracket 29, which bracket 29 is in turn secured to the base 6. The spring 28 co-operates with the notches in the rack 26 in such a manner that the spring 28 assists or snaps the carriage C from one position to the other when the magnet MM is being operated.

The secondary carriage SC, as before mentioned, is slidably supported by the carriage support 30, in the following manner. The side plates 31 and 32 are pivotally secured to a block 33 by means of pivot screws 34, the said block 33 being securely fastened to the carriage C in any desirable manner. The forward end of the carriage support 30 rests upon a block 35, which block 35 is secured to the carriage C. The carriage SC comprises a block 36 slidably supported by means of a square rod 37, which rod 37 is secured at its ends to the cross pieces 38, which cross pieces are in turn secured to the side plates 31 and 32. The secondary carriage SC supports a combined test and wiper control relay TWR, the said relay comprising a heel iron 39, electromagnet 40, pole piece 41, armatures 42 and 43, and a set of contact springs 68, 69, 70 and 71 mounted on the bracket 72 and insulated therefrom, the said springs being operatively associated with the armature 43. The armature 42 is pivotally supported by the heel iron 39 at 44 and is provided with an extension 42', which extension 42' forms a support for the wiper carrying arm WA which is in the form of a rod 45 pivotally supported by the extension 42'. The arm 45 is provided with a stop 46 which engages a stop 47 in the extension 42' and is held in

this position by means of the coil spring 48 whose tension is such that it holds the stop 46 against the stop 47. The armature 43 is pivotally supported by the heel iron 39 at the point 49 and is provided with an angular extension 43' which is provided with a nose 43² that is in operative association with the notch 50 in the side plates 31 and 32 for purposes as will be more fully hereinafter described. The wiper carrying arm WA supports a group wiper 51 and the line wipers 52 and 53, private wiper 54 and auxiliary wiper 55, the said wipers 51, 52, 53, 54 and 55 are secured to the arm 45 and properly insulated from the arm 45 and from each other.

I provide a set of group contacts GC comprising ten contacts 56 supported upon the plate 57 and insulated therefrom and from each other, for co-operation with the wiper GW. The contact bank B comprises ten groups of contacts, each group of contacts comprising ten sets of four contacts each; each set including line contacts 58 and 59, a private contact 60 and an auxiliary contact 61, the said contacts being operatively associated with the wipers 52, 53, 54 and 55. The sets of contacts 58, 59, 60 and 61 are supported by plates 62 which plates 62 are angularly disposed in relation with the group contacts 56. Terminals 63 are provided for the contacts 58, 59, 60 and 61; the said terminals 63 being also secured to the plates 62. The terminals 63 are connected to the bank contacts 58, 59, 60 and 61 by means of fine conductors not shown. The bank wires (not shown) are connected to the bank terminals 63. The plates 62 are provided with angular portions 64 in the form of a rail, the said rails 64 being provided with a plurality of notches 65 which are successively engaged by the arm 45 when the wipers 52, 53, 54 and 55 move over the successive sets of contacts 58, 59, 60 and 61 in search of an idle set of contacts. The group wiper 51 is provided with an angular portion 51' which is adapted to engage the angular extension 56' of the group contacts 56. A U-shaped member 66 secured to the extension 42' in a suitable manner has its depending arms 66' resting in the notch 67, whereby when the side pieces 31 and 32 are moved, the magnet TWR and its associated mechanism will also be moved. A set of normally closed contacts 75 is insulatingly secured to the end plate 4 and when the carriage C is in normal position, an insulation button 76 carried upon an angular bracket 77 holds the contacts 75 in their normal position, but upon the first step of the carriage C off normal, the contacts 75 assume their alternate position. Three sets of contacts 78, 79 and 80 are insulatingly mounted upon the end plate 5 and upon the last step of the carriage C, insulation buttons 81 secured to the bracket 82 engage the spring sets 78, 79 and 80 and move

them to their alternate positions. A plate 83 suitably secured to the base 6 serves as a mounting means for the conducting strips 84, 85, 86, 87, 88 and 89, the said strip 84 being engaged by the wiper 90, strips 85, 86 and 87 by the wiper 91 and the strips 88 and 89 by the wipers 92 and 93 for controlling circuits, to be hereinafter described. While I have shown a certain combination of contact strips and wipers, I do not wish to be limited to the same as any number of contact wipers and strips may be provided as found necessary to control any specific circuit arrangement.

Referring now to the structure as illustrated in Figs. 5 and 6, I show a modified form of driving mechanism for the selector described and illustrated in Figs. 1 to 4, inclusive. When using the driving mechanism as illustrated in Figs. 5 and 6, the motor magnet MM, racks 11 and 12 and the shifting mechanism for the racks 11 and 12 are dispensed with and the rectangular shaped frame 100 is substituted and is secured to the bottom of the carriage C. The means for driving the carriage C in a horizontal direction will now be described. A common driving shaft 101 is provided and supplied with a plurality of driving wheels 102 such a wheel as 102 being associated with each switch of a group. The shaft 101 is centrally located in relation to the frame 100 and the drive wheel 102 is in frictional engagement with a wheel 103 loosely journaled on a shaft 104. Plates 105 and 106 are provided each being provided with an arcuate slot 107 in which the shaft 104 rests. The wheel 103 and the shaft 104 upon which the wheel 103 is mounted as a whole is centrally located in relation to the frame 100 and is held in its intermediate position in the arcuate slot 107 by means of the springs 108 and 109, the said springs being suitably mounted upon a bracket 110 by means of rivets 111. The free ends of the springs 108 and 109 engage collars suitably secured to the shaft 104. To move the wheel 103 into engagement with either the faces 112 and 113 of the frame 100 to drive the carriage C forward or backward, I provide a pair of operating magnets 114 and 115 supported by the heel iron 116, which heel iron 116 is in turn secured to a base 117. An armature 118 is pivotally supported by the heel iron 116 and rests between the magnets 114 and 115. The armature 118 is provided with a bifurcated end 119, and a collar 120 is placed on the shaft 104 and rests in the bifurcated end 119 of armature 118.

Having described the apparatus, I will now describe its operation, assuming first that the carriage C is to be moved forward, the magnet 114 is energized attracting the armature 118. The bifurcated end 119 engaging the collar 120, moves the wheel 103

4

and shaft 104 as a whole, in the arcuate slot 107, against the tension of the springs 108. The wheel 103 now engages the face 112 of the frame 100, and as the wheel 103 is in frictional engagement with the driving wheel 102, transmits motion to the frame 100 to move the same. Since the frame 100 is secured to the carriage C, the said carriage C is moved in a forward horizontal direction until the limit of its forward motion is reached when the circuit of the magnet 114 is opened and the spring 108 now moves the wheel 103 to its intermediate position. To restore the carriage to normal, the magnet 115 is actuated to attract the armature 118 and the bifurcated end 119 engaging the collar 120 on the shaft 104, moves the wheel 103 into engagement with the face 113 of the frame 100 against the tension of the spring 109, and a rearward horizontal motion of the frame carries the carriage C to normal, and when the carriage C returns to normal, the magnet 115 restores. Due to the action of spring 109, the wheel 103 is restored to its intermediate position out of engagement with the face 113 of frame 100 when the frame has again reached normal.

To accomplish the energization of the magnets 114 and 115, respectively, to transmit motion to the carriage C in either direction, I provide a circuit changing mechanism clearly illustrated in Figs. 7 and 8. The circuit changing mechanism comprises an interrupter disk 121, star wheel 122 and a ratchet 123, all of which are supported upon the shaft 124, which shaft 124 is suitably supported at its opposite ends in the plates 125 and 126, which plates 125 and 126 are secured to a base 126'. The interrupter disk 121 is provided with a plurality of notches 127 and lugs 128 upon the peripheral ring 129 which is of suitable insulation material, the said notches 127 and lugs 128 are operatively associated with the spring 131 of the spring set which comprises the springs 130, 131 and 132. The springs 130, 131 and 132 are insulatingly mounted upon a suitable bracket 133 which bracket 133 is in turn secured to the base 127. A stepping magnet 134 is provided and comprises an electromagnet 135, a heel iron 136, an armature 137 and a pawl 138 pivotally supported upon the forward end of the armature 137, the said pawl 138 being spring pressed into engagement with a tooth of the ratchet 123. The stepping magnet 134 as a whole is secured to the base 126' by means of screws not shown. A roller 139, spring pressed into engagement with the star wheel 122, is pivotally carried by the support 140.

Now, upon the energization of the stepping magnet 134, its armature 137 is attracted, causing the pawl 138 which engages a tooth of the ratchet 123 to rotate the interrupter disk 121, star wheel 122, ratchet

123 and shaft 124 one step. This movement of the interrupter disk 121 causes the spring 131 which normally rests upon the periphery 141 to disengage the same and drop into a notch 127 in the interrupter disk 121. This movement of spring 131 causes it to engage its associated contact 132 to close a circuit for, say the magnet 114 of the driving mechanism just described. The magnet 114 upon actuation attracts its armature 118 causing the wheel 103 to be moved into engagement with the surface 112 of the frame 100. This causes a forward movement of the carriage C and when the said carriage C reaches the limit of its travel, means are actuated to open the circuit of the stepping magnet 134. When the star wheel 122 is rotated one step as just described, the roller 139 and its supporting arm 142 are forced out against their normal tension and the roller engages a tooth of the star wheel 122. Now, upon the retraction of the armature 137 of magnet 134, the roller, due to its spring pressed action, rotates the shaft 124, interrupter disk 121, ratchet 123 and star wheel 122 the distance of one step, and this movement of the interrupter disk 121 causes the spring 131 to leave the notch 127 and to again engage the periphery 141 of the disk. This allows the spring 131 to disengage spring 132 to open the circuit of the magnet 114, allowing the carriage to remain in its advanced position. The ratchet 123 also having been moved, the pawl 138 now engages the next tooth of the ratchet 123. To return the carriage C to normal, means are actuated to operate the stepping magnet 134 again, and the armature 137 upon attraction causes the pawl 138 to step the interrupter disk 121, star wheel 122, ratchet 123 and shaft 124 one step. The stepping of the interrupter disk 121 causes the periphery 141 to disengage the spring 131 and causes the lug 128 to engage the spring 131 moving it into engagement with the spring 130. The closure of contacts 130 and 131 closes an energizing circuit for the magnet 115 of the driving mechanism and its armature 118 is attracted, causing the wheel 103 to engage the surface 113 of the frame 100, causing the carriage C to be moved to its normal position, and when this position is reached, means are actuated to open the energizing circuit of the stepping magnet 134 which magnet retracts its armature 137 allowing the spring pressed roller 139 to move the star wheel 122 another step, as above described, and this step which is also taken by the interrupter disk 121 causes the lug 128 to disengage the spring 131 and again allow the spring 131 to engage the periphery 141 of the disk 121, placing the spring 131 in an intermediate position between the springs 130 and 132. The opening of contacts 130 and 131 opens the energizing cir-

cuit of the magnet 115 allowing it to retract its armature 118, disconnecting the wheel 103 from the face 113. The ratchet 123 having been moved also, allows the pawl 138 to engage the next tooth of the ratchet 123. This sequence of operation of the mechanism is continued for the advancement and restoration of the carriage C.

Referring now to the connector mechanism as illustrated in Fig. 9, it comprises a mechanism similar in construction to that described in connection with the selector illustrated in Figs. 1 to 4, inclusive. It comprises in general a carriage C' and a secondary carriage SC'; a stepping magnet MM² and rack shifting mechanism. The test relay TWR² associated with the secondary carriage SC' is somewhat different in construction as is also the secondary carriage support, as will now be described, 10

The relay TWR² is provided with a pair of armatures 42' and 43² pivotally supported by the heel iron 39', and a pair of pole pieces 41' and 41² are provided for 15 the armatures 42' and 43². The side supports 31' and 32' are provided with a plurality of notches 50' with which armature 43² is operatively associated. Now, when 20 the switch is in its normal position, the arm 66² of the member 66³ rests in the notch 67'. When the motor magnet MM² is energized 25 and de-energized, as described in connection with Figs. 1 to 4, inclusive, the carriages C' and SC' are stepped in a horizontal direction by the magnet MM² until the group 30 wiper engages a group contact which is grounded, due to the said contact being pre-selected by the tens group selecting switch. When this grounded contact is engaged by 35 the group wiper, the relay TWR² is energized, attracting its armatures 42' and 43² and the attraction of armature 42' withdraws arm 66² from the notch 67' and places 40 wiper arm 45' in engagement with the inclined rail 64' of the selected group and the 45 attraction of armature 43² withdraws the nose of the said armature from the engaged notch 50'. The motor magnet MM² continues to step the carriage C' forward after 50 the group contact has been selected, but the secondary carriage SC' as this movement of carriage C' continues, remains in its adjusted position, due to the nose of armature 43² having disengaged notch 50' and the 55 wiper arm 45' engaging the rail 64'. Upon the eleventh step of the carriage C' and carriage support for carriage SC', the relay TWR² de-energizes, allowing the nose of armature 43² to engage a notch 50'. The 60 continued energization and de-energization of magnet MM² continues to step carriage C' in a horizontal direction and as armature 43² again engages a notch 50', the secondary carriage is again moved but in an angular 65 direction, due to the arm 45' engaging the

inclined rail 64', the wipers engaging successive sets of contacts and when the wipers engage the contacts of the wanted line, the private contact is grounded, due to its having been so conditioned by the units pre-selector, and this grounded contact again closes an energizing circuit for relay TWR² which again attracts its armature 43² again disengaging its nose from a notch 50'. The movement of carriage SC' is thus arrested 70 and the wipers remain in engagement with the selected set of contacts due to the arm 45' engaging a notch 65' in the inclined rail 64'. The magnet MM² continues to step the carriage C' and carriage support for carriage SC' until carriage C' reaches its foremost position at which time the shifting mechanism shifts the racks, as already described in connection with Figs. 1 to 4, inclusive. 75

In Fig. 10, I show a group selecting switch, one of these switches being provided for each selector switch. This switch is also used as a tens and units pre-selector for the connector switch, that is, two 80 switches of this character are provided for each connector. The switch as shown comprises a driving magnet 219, an armature 401 provided with a driving pawl 402 adapted to rotate the ratchet 403 for each de- 85 energization of the magnet 219. A wiper 222 is carried by the ratchet 403 and is adapted to engage the bank contacts 223. A set of off-normal contacts 224 is also provided as well as a retaining pawl 407. The 90 retaining pawl 407 is adapted to be tripped by the switch carriage C or C' of the selector or connector switch depending upon which of these switches this apparatus is associated with. Said retaining pawl is normally held 95 out of engagement with ratchet 403. A 100 complete description of the operation of this apparatus will be hereinafter given. 105

Referring now to Figure 11, which comprises Sheets 1, 2 and 3, I here show the 110 necessary apparatus for establishing a connection between a calling subscriber A and a called subscriber H. On Sheet 1, I show a calling substation A, together with its line circuit equipment L, located at the central 115 office, an operator's cord circuit D, together with an operator's telephone set O, and a set of multiple jacks TJ connected to a trunk circuit leading to a first selector switch E, shown on Sheet 2. The selector 120 switch E shown on Sheet 2 is adapted to extend connection to a second selector switch F shown on this sheet. The second selector switch F is adapted to extend a connection to the connector switch G shown on Sheet 3, 125 which connector switch is adapted to extend a connection to the called substation H shown at the right of Sheet 3, together with its line circuit equipment L'.

The substation A, shown on Sheet 1, and 130

the substation H, shown on Sheet 3, are of the ordinary Kellogg common battery type, while the line circuit equipment L and L' contain the usual line relays and cut-off relays, together with multiple jacks J and J', respectively. The cord circuit D is provided with the necessary supervisory apparatus, together with an operator's calling device ID, which is diagrammatically illustrated. The first selector E and second selector F, shown on Sheet 2, comprise the necessary line relays, motor magnets, wipers, etc., to permit them to operate successfully with the switch structures shown in Figs. 1 to 10, inclusive. A complete description of this apparatus will be hereinafter given when the manner in which a complete connection is established between the calling substation A and the called substation H is given.

The connector switch G is provided with the necessary relays, contacts, wipers, ringing generator, interrupters, etc., as to permit it to operate with the switch structure shown in Figs. 1 to 10, inclusive. Likewise, a complete description of the operation of the connector switch will be hereinafter given. The system as shown, is of the well-known Lundquist trunking system type, and is of 10,000 line capacity, being provided with first selector, second selector and connectors. If it is desired to increase the capacity of the system, a third selector may be added, while if it is desired to decrease the capacity of the system, the second selector and even the first selector may be dispensed with and the trunk jacks connected directly through to the connector switch G.

Referring now more in detail to my invention as illustrated and assuming that the subscriber at the calling substation A initiates a call, the removal of the receiver at the calling substation A establishes an energizing circuit for the line relay LR of the line circuit L, traced from battery through the winding of line relay LR, normal contact 200 of the cut-off relay CO, through the substation A to ground at normal contact 201 of the cut-off relay CO. The line relay LR upon energization closes its alternate contact to establish a circuit for the line signal S traced from battery through the lamp S to ground at the alternate contact of line relay LR, which causes the said signal S to glow. The operator noting the lighted signal S, inserts the answering plug AP of the cord circuit D into the answering jack J of the calling line, establishing an energizing circuit for the cut-off relay CO traced from ground through the winding of the said relay CO, sleeve contacts of the connected plug AP and jack J, normal contact 202 of supervisory relay SR, through the supervisory lamp AL to battery and ground. The relay CO, upon energization opens its normal contacts 200 and 201 interrupting the circuit of line relay LR, which relay LR restores and effaces the line signal S. The insertion of the answering plug AP into the jack J of the calling line also establishes an energizing circuit for the supervisory relay SR traced from battery through the upper winding of the relay SR, the tip contacts of the connected plug AP and jack J, through the substation A through ring contacts of the connected jack J and plug AP to ground through the lower winding of the supervisory relay SR. The relay SR upon energizing closes its alternate contact 203 closing a substitute circuit for the cut-off relay CO traced from battery through alternate contact 203, sleeve contacts of the connected plug AP and jack J to ground through the winding of the cut-off relay CO. The private contacts 204 of the connectors associated with the calling line are made busy, due to the battery potential placed upon the sleeve of the jack when the plug is inserted into the jack J of the calling line. This battery potential extends over conductor 205 to the private contacts 204, thus making them busy against all incoming calls which may be extended to the calling subscriber at substation A. The operator after inserting the plug AP into the jack J actuates her listening key LK to connect her operator's set O to the cord conductors and now inquires the wants of the calling subscriber at substation A. Assuming that it is the subscriber at the called substation H that is wanted, the operator now tests one of the trunk jacks TJ as to its idle or busy condition by placing the tip of the calling plug CP to the sleeve of the trunk jack TJ and if the jack TJ tested leads to a busy first selector E, the sleeve of the jack TJ will have a battery potential upon it and the operator will receive the usual click in her head receiver. Assuming that the trunk jack TJ leads to an idle first selector as E, the operator inserts the calling plug CP into the trunk jack TJ and this insertion establishes an energizing circuit for the sleeve relay SL traced from battery through the winding of the said relay SL, conductor 206, sleeve contacts of the connected plug CP and jack TJ to ground, and the relay SL upon energization closes its alternate contact 209 closing the continuity of the talking conductor.

Assuming further that the number of the called subscriber at substation H is 2232, the operator now actuates her dial key DK to connect her impulse device ID to the calling end of the cord conductors. The actuation of the dial key DK after the insertion of the calling plug CP into a trunk jack TJ closes an energizing circuit for the primary

relay PR of the first selector E traced from battery through the winding of the said primary relay PR, conductor 207, normal contact 78 of the circuit switch S, tip contacts of the connected plug CP and jack TJ, alternate contact 210 of the dial key DK, impulse spring 211 of the impulse device ID, alternate contact 212 of the dial key DK, ring contacts of the connected plug 10 and jack CP and TJ to ground at normal contact 80 of the circuit switch S'. Primary relay PR upon energization, closes its alternate contact 208 establishing an energizing circuit for the motor magnet MM traced 15 from ground through alternate contact 208 of relay PR, conductor 214, normally closed contact 75 of the circuit switch S³, conductor 215, normal contacts 73 and 74 of the motor magnet MM, through the winding of the 20 said magnet MM, conductor 226 to battery and ground at normal contact 79. The motor magnet MM upon energization, attracts its armature 8 causing the pawl 16 which is engaging a tooth of the rack 11 25 to step the carriage C and secondary carriage SC one step forward in a horizontal direction. The secondary carriage is also carried this step, due to the arms 66' engaging the notch 67. The armature 42, associated with the relay TWR and carried by the secondary carriage SC, supports the wiper arm 45 which carries the group wiper 51, line wipers 52 and 53, private wiper 54 and auxiliary wiper 55, the said wipers being 30 normally two steps distant from their associated bank contacts, and upon this first step of the switch the wipers are placed one step distant from their associated bank contacts. Upon the first step forward from 35 zero position, the buffer 76 disengages contacts 75 permitting the same to assume their alternate position, opening the initial energizing circuit of the motor magnet MM. Upon the first step of the carriage C, off- 40 normal wipers 90, 91, 92 and 93 are also moved forward one step, wiper 90 remaining in engagement with strip 84, wiper 91 engaging strip 86, and wipers 92 and 93 engaging strips 88 and 89, respectively. In 45 the circuit, the circuit switch S⁴ represents wiper 91 and strip 86, and circuit switch S⁵ represents wiper 93 and strip 89. Strip 87 represents switch S⁶. The wipers 90 and 92 and strips 83 and 88 are short circuiting 50 strips and wipers for connection purposes with strips 85, 86 and 87, and strip 89 as is readily apparent. That is, wipers 90 and 91 are electrically connected together and wipers 92 and 93 are electrically connected. 55 By this arrangement, it is unnecessary to provide flexible cords for these switches. Switch S⁴ moves to its alternate position upon the first step, closing its alternate contact 216, and the switch S⁵ also moves to its alternate position to close its alternate contact 217. The operator now actuates her impulse dial ID to send the first set of impulses which are two in number, having assumed the number of the called subscriber at substation H to be 2322. These two impulses cause two interruptions of relay PR causing two de-energizations of the said relay PR. Upon the first de-energization of the relay PR the closure of its normal contact 218 establishes an energizing circuit 60 for the stepping magnet 219 of the pre-selector switch PSS (the switch shown in Fig. 10) traced from battery through the winding of the magnet 219, conductor 220, alternate contact 217 of the switch S⁶, conductor 221 to ground at normal contact 218 of relay PR. By means of the ratchet and pawl mechanism, the wiper 222 of the switch PSS is stepped into engagement with the first contact 223. The second impulse again de-energizes the relay PR, again closing the circuit for magnet 219 to step the wiper 222 into engagement with the second contact 223. Upon the first step of the switch wiper 222 off normal, off-normal contact 224 assumes its alternate position, closing an energizing circuit for the motor magnet MM traced from ground at alternate contact 224, through conductor 225, through alternate contact 216 of the switch S⁴, conductor 215, normal contacts 74 and 73, through the winding of motor magnet MM and conductor 226 to battery and ground at normal contact 79 of the switch S². 65 The motor magnet MM upon its energization causes the carriages to be stepped a second step in a forward direction. This movement causes wiper 91 to disengage strip 86 and engage strip 87 thereby causing (referring to circuit diagram) the switch S⁴ to open its contact 216 and switch S⁶ to close its alternate contact 227. The switch is so adjusted that the primary relay delivers its second impulse to the magnet 219 of the pre-selector switch PSS to cause 70 it to move its wiper 222 to the second bank contact 223 before the motor magnet MM moves the group wiper 51 onto the first group contact 56, providing there is more than one impulse to be transmitted to the magnet 219 by the primary relay PR. The magnet MM is also adapted to operate slightly slower than the rate that relay PR sends impulses to magnet 219 to prevent the group wiper from being moved to group contacts before the wiper 222 has been moved to the corresponding contacts 223. The motor magnet MM stepping the carriage C and secondary carriage SC a second step, causes the group wiper 51 to engage the first group contact 56. The closing of alternate contact 227 of the switch S⁶ closes another energizing circuit for the motor magnet MM, which was interrupted 75 when contact 216 assumed its normal position. 80

tion on the second horizontal step of the switch, traced from ground at alternate contact 227, over conductor 215, through contacts 73 and 74, winding of motor magnet MM, conductor 226 to battery and ground at normal contact 79 of switch S². The motor magnet MM upon energization, steps the carriages C and SC a third step in a forward direction, placing the group wiper 51 into engagement with the second group contact 56. The wiper 222 being grounded, places a ground upon the second contact 223 in which it remains in connection, the magnet 219 having received two impulses from relay PR, this ground extends over conductor 228, to the second contact 56 of the group contacts. When the group wiper 51 engages this grounded contact, a circuit is established for the relay TWR traced from battery through the winding of relay TWR over conductor 229, through wiper 51, contact 56, conductor 228, contact 223 and wiper 222 to ground. The relay TWR upon energization attracts its armatures 42 and 43 and the attraction of armatures 43 brings about the movement of the springs 68, 69, 70 and 71 to their alternate positions and the nose 43² of the angular end 43' of the armature drops into the notches 50, and the attraction of armature 42 causes the arms 66' to leave the notches 67 and causes the arm 45 to engage the rail 64 of the plate 62. The motor magnet MM upon its third energization opens its contacts 73, 74 opening the circuit of magnet MM which again restores, and closing of contacts 73 and 74 again establishes a circuit for motor magnet MM, as before described, stepping the carriage C forward a fourth step. The arm 45 engaging the angular rail 64 of the plate 62 causes wipers 52, 53, 54 and 55 to engage the first set of contacts 58, 59, 60 and 61. The energization of magnet TWR causes the raising of the group wiper 51 from engagement with the contact 56, but the wiper 51 is provided with an angular extension 51' which engages the angular portion 56' until the instant the wipers 52, 53, 54 and 55 engage contacts 58, 59, 60 and 61, so that the relay TWR is insured of a positive and continuous energization until the first set of contacts is engaged. The nose 43² engaging the notch 50 the carriage support 30 as a whole is carried forward in an angular direction due to the arm 45 engaging the rail 64, and due to the continued energizations of the motor magnet MM, the carriage C is, of course, stepped in a horizontal direction. The wipers 52, 53, 54 and 55 having engaged the first set of contacts 58, 59, 60 and 61, should the first private contact 60 be busy, a substitute circuit for relay TWR is established after wiper 51 disengages contact 56 before relay TWR has de-energized, traced from battery through the winding of relay TWR contacts 70 and 71, conductor 230, conductor 231, wiper 54, to the grounded contact 60. The relay TWR remains energized as long as busy contacts are found. The relay TWR remaining energized, the nose 43² is held in the slot 50 and the next energization of MM steps carriage C another horizontal step and the movement of carriage C moves the wipers 52, 53, 54 and 55 into engagement with the second set of contacts 58, 59, 60 and 61. Now assuming that the second set is idle, the private contact 60 will be free from ground due to the fact that the contacts lead to an idle second selector F, thus opening the locking circuit of the relay TWR. The armature 43 of relay TWR retracts allowing its nose 43² to disengage the notch 50, thereby permitting the wipers 52, 53, 54 and 55 to remain in engagement with the selected set of contacts 58, 59, 60 and 61. The arm 45 resting in a notch 65 in the rail 64 holds the wipers in place on the selected contacts. The closing of contact 68 of relay TWR supplies a busy potential through wiper 54 to the multiple contact 60. The continued energization and de-energization of motor magnet MM steps the carriage C step by step in a horizontal direction until it has taken its twenty-second step, but the carriage SC remains stationary after having selected an idle set of contacts, but the angular movement of the secondary carriage support 30 continues and the rod 37 passes through the opening in the block 38 of the carriage SC. The motor magnet, as before mentioned, continues to advance the carriage C until twenty-two steps have been taken by it. Upon the twenty-second step of the carriage C, the buffer 81 engages the spring sets 78, 79 and 80 moving them to their alternate position. The closing of alternate contacts 78 and 80 extends the line conductors to the idle second selector and the closing of alternate contact 79 of the switch S² opens the energizing circuit of magnet MM, preventing further energizations of the motor magnet MM at this time. Upon the twenty-second step of the carriage C in a horizontal direction, the cam edge 19 of the plate 18 engages the post 20 moving the rack 11 out of line with the pawl 16 and the rack 12 in operative relation with the pawl 17 of the motor magnet MM.

The idle second selector switch F having been seized, an energizing circuit for the primary relay PR' of the second selector switch F is established traced from battery through the winding of relay PR', conductor 233, normal contact 234 of the switch S², contact 58, wiper 52, alternate contact 78, tip contacts of the connected plug and jack CP and TJ, alternate contact 210, normal contact 211, alternate contact 212, ring contacts of the plug CP and jack TJ, alternate 125

130

contact 80, wiper 53 and contact 59, to ground at normal contact 237 of switch S^8 . The contacts 78 and 80 are closed to cause the energization of PR' before contact 79 is moved to its alternate position to supply relay RR with current. The primary relay PR' upon energization opens its normal contact 238 opening the release circuit, thus preventing a premature release of the first 10 selector switch E . The closing of alternate contact 239 of relay PR' establishes an energizing circuit for the motor magnet MM' traced from ground through alternate contact 239 of relay PR' , through conductor 240, normal contact 241 of switch S^9 , conductor 242, normal contact 243 of MM' , the winding of magnet MM' , conductors 244 and 245 to battery and ground at normal contact 246 of the switch S^{10} . The magnet MM' energizing, steps the carriages C and SC one step, thus placing the group wiper 247, which is normally two steps distant, one step distant from the group contacts 252. The stepping of the carriage C allows the switch S^9 to assume its alternate position and the opening of its normal contact 241 opens the energizing circuit of the motor magnet MM' as described in connection with the first selector E . The second selector switch upon its first 20 step from zero position allows the switch S^{11} to assume its alternate position to open its normally closed contact 258, and the switch S^{12} also assumes its alternate position closing its normally open contact 259. The switch S^{13} also assumes its alternate position to close its normally open contact 260.

The second selector F having been selected and its first preliminary step taken, the operator now actuates her impulse device to 30 send three impulses of current which causes three interruptions of the circuit of relay PR' . Upon the first de-energization of relay PR' an energizing circuit is closed for the stepping magnet 261 of the pre-selector switch PSS' traced from battery through the winding of the magnet 261, conductor 262, closed contact 259, and conductor 263 to ground at normal contact 264 of relay PR' . The switch PSS' is similar in construction to the switch shown in Fig. 10. The energization of magnet 261 steps wiper 265 of the switch PSS' into engagement with the first contact 266 of the switch PSS' . Two more de-energizations of relay PR' are brought about by the impulse device ID causing two more energizations of the magnet 261, as just described, to step the wiper into engagement with the third contact 266 which places a ground upon the 40 third group contact 252 rendering it selectable, the ground extending from grounded wiper 265 through contact 266, and conductor 267 to the third group contact 252. Upon the first step of the wiper 265 off normal, the off-normal contact 268 associated with the switch PSS' assumes its alternate position, closes a circuit for the motor magnet MM' traced from ground through alternate contact 268, conductor 269, alternate contact 260, conductor 242, normal contact 243 of magnet MM' , through the winding of magnet MM' , conductors 244 and 245 to battery and ground at normal contact 246. As stated in connection with switch E , second selector 50 F is so arranged that the motor magnet MM' operates slightly slower than the rate at which impulses are transmitted, and group wiper 247 does not move onto a group contact until wiper 265 has moved off of a 55 multiple contact, unless the wiper 265 is to remain in connection with such multiple contact.

The motor magnet MM' upon energization opens its contact 243 interrupting its 60 circuit, and upon de-energization again closes its circuit. The motor magnet thus steps the carriage C and secondary carriage SC in a horizontal direction and when the group wiper 247 engages the elected contact 252, which is now grounded, an energizing circuit for the relay TWR' is established traced from battery through the winding of the relay TWR' , conductor 271, wiper 247, contact 252, conductor 267, contact 266 and wiper 265 to ground. The relay TWR' upon energization attracts its armatures as described in connection with first selector E . The further energization of magnet MM' causes the secondary carriage SC to move forward in an angular direction, causing the wipers 246, 249, 250 and 251 to engage the first set of contacts 253, 254, 255 and 256 and should the first set of contacts engaged lead to a busy connector, the private contact 255 would be grounded, closing a locking circuit for the relay TWR' traced from battery through the winding of relay TWR' , alternate contact 272 of relay TWR' , conductors 273 and 274, wiper 250 to the ground private contact 255. The initial energizing circuit of relay TWR' is opened the instant the wipers 246, etc., engage the first set of contacts 253, etc., should the set engaged be idle, for purposes as already described. The motor magnet MM' continues stepping the carriages C and SC , and the relay TWR' remains energized due to the wiper 250 engaging successive grounded contacts 255, until an idle contact 255 is reached at which time the circuit of the relay TWR' is opened due to the idle contact being free from ground. The wipers 246, 249, 250 and 251 remain in engagement with the idle sets of contacts 253, 254, 255 and 256 which lead to an idle connector G by the means already described. The motor magnet MM' continues to step the carriage C and the carriage support of the carriage SC until the twenty-second step 100

is reached when switches S^7 , S^8 and S^{10} assume their alternate positions, the switch S^{10} closing its alternate contact 246 and opening the circuit of magnet MM' , preventing further actuation of the magnet MM' at this time. The switches S^7 and S^8 assuming their alternate positions close their alternate contacts 234 and 237, closing the continuity of the talking conductors 10 and extend the calling subscriber to the idle connector G selected. As before stated, S^7 and S^8 operate before S^{10} closes the circuit of RR' . The primary relay PR' also restores due to the contacts 234 and 237 assuming their alternate positions.

Upon the closure of contacts 234 and 237 an energizing circuit for the primary relay PR^2 of the connector G is established, traced from battery through the winding 20 of the primary relay PR^2 , normal contact 275 of the switch S^{15} , normal contact 276 of switching relay 277, contact 253, wiper 246, alternate contact 234 of switch S^7 , contact 58, wiper 52, alternate contact 78, tip 25 contacts of the connected trunk jack TJ and plug CP, alternate contact 210, normal contact 211, alternate contact 212, ring contacts of the plug CP and jack TJ, alternate contact 80, wiper 53, contact 59, alternate contact 237, wiper 249, contact 254 and normal contact 278 of relay 277 to ground at normal contact 279 of the switch S^{16} . The primary relay PR^2 upon its energization closes its alternate contact 280, and opens its normally closed contacts 281, 282. The closing of alternate contact 280 of relay PR^2 establishes an energizing circuit for the motor magnet MM^2 of the connector G traced from ground at alternate contact 280, 30 through conductor 283, normal contact 284 of the switch S^{17} , conductor 285, normal contact 286 of magnet MM^2 , and through the winding of magnet MM^2 to battery and ground. The magnet MM^2 upon energization, steps the carriage C' and secondary carriage SC' one step in a horizontal direction. When the switch takes its first step from zero position, the alternate contact 284 of the switch S^{17} opens the initial energizing circuit of magnet MM^2 . The switches S^{18} and S^{19} , upon the first step of the switch, assume their alternate positions, switch S^{18} opening its normal contact 287 to prevent a premature release circuit being closed when relay PR^2 is de-energized, and switch S^{19} closing its alternate contact 288 to prepare a circuit for magnet 289.

The operator now actuates her impulse device ID, sending two impulses of current 60 causing two interruptions of the circuit of primary relay PR^2 , and upon the first de-energization of relay PR^2 an energizing circuit is established for the stepping magnet 289 of the pre-selector switch PSS^2 traced from battery through the winding of mag-

net 289, conductor 290, alternate contact 288, conductor 291, normal contact 292 of the switch S^{20} to ground at normal contact 282 of relay PR^2 . The magnet 289 steps the wiper 293 of the switch PSS^2 into engagement with the first contact 294 with which the wiper is associated. The switch PSS^2 is the same as the switch shown in Fig. 10. The second de-energization of relay PR^2 causes a second energization of magnet 289 70 causing the wiper 291 to be stepped into engagement with the second contact 292. Upon the first step of the wiper 293 off normal, its off-normal contact 294 moves to its alternate position and as switch S^{17} has 80 closed its alternate contact 284, an energizing circuit is established for the magnet MM^2 traced from battery through the winding of magnet MM^2 , its normal contact 286, conductor 285, alternate contact 284 to 85 ground at alternate contact 294. The magnet MM^2 steps the wiper 295 into engagement with the first contact 296. The wipers 297, 298, 299 and 300 are also stepped, but at this time do not engage any of the contacts 301, 302, 303 or 304. Upon the second step of the switch, switch S^{21} assumes its alternate position closing its alternate contact 305, closing circuit for the magnet MM^2 traced from battery through magnet 90 MM^2 , its contact 286, conductor 285 and alternate contact 305 to ground. Alternate contact 284 of switch S^{17} is opened upon the second step of magnet MM^2 . This steps the wiper 295 into engagement with the second 100 contact 296 establishing an energizing circuit for the relay TWR^2 traced from battery through normal contact 306 of switch S^{22} , conductor 307, through the winding of relay TWR^2 , conductors 308 and 309, wiper 105 295, contact 296, conductor 310, and contact 294 to grounded wiper 293. The wiper 293 being permanently grounded, places a ground upon the selected contact 296, making it selectable by the wiper 295 when it 110 engages the same. The relay TWR^2 upon energization attracts its armatures 42' and 43' (Fig. 9) and the attraction of armature 43' causes the said armature to withdraw its nose from engagement with notch 50', 115 and the armature 42' upon attraction withdraws the arm 66' from the notch 67'. The movement of armature 42' causes arm 45' to engage the rail 64' of the selected group and the further actuation of magnet MM^2 , 120 due to the closed contact 305 and its interrupter contact 286, causes the carriage C' and the support for secondary carriage SC' to move in a horizontal direction, but the secondary carriage SC' remains stationary, 125 due to the engagement of arm 45' with the rail 64', and the rod 37' thus slides through the opening in the support 36'.

The relay TWR^2 remains energized until contact S^{22} is opened. Upon the eleventh 130

step of the carriage C' off normal, the switch S²¹ opens its contacts to open the energizing circuit of the motor magnet MM² and the switch comes to rest. The switch S²² also opens its contact 306 bringing about the de-energization of relay TWR² and the switch S²³ also assumes its alternate position, closing its alternate contact 311, as does also switch S²⁰ causing it to close its alternate contact 292. The relay TWR² de-energizing permits its armature to drop into a notch 50' on the pivoted rail of the carriage SC'.

The operator now actuates her impulse device ID to send two impulses of current, which impulses cause two interruptions of the primary relay PR² which brings about two energizations of the stepping magnet 312 associated with the pre-selector switch PSS³, traced from battery through the winding of magnet 312 and alternate contact 292 to ground at normal contact 282. Each time relay PR², is de-energized, magnet 312 rotates its wiper 313 one step. The switch PSS³ is the same in construction as the switch shown in Fig. 10. The stepping magnet 312 steps its associated wiper 313 of switch PSS³ into engagement with its second associated contact 314, placing ground upon the second contact 304, rendering it selectable. Upon the first step of the wiper 313 off normal, its off-normal contact 315 assumes its alternate position closing an energizing circuit for magnet MM² traced from battery through the winding of magnet MM², normal contact 286, conductor 285 and alternate contact 311 to ground at alternate contact 315. The magnet MM² upon this twelfth step moves the wipers 297, 298, 299 and 300 into engagement with the first set of contacts 301, 302, 303 and 304. As stated in connection with the selectors, the magnet MM² operates slightly slower than the rate that impulses are transmitted and the wipers 295 and 300 are not moved into engagement with contacts 296 and 304, respectively, until wipers 293 and 313 have moved off of multiple contacts 294 and 314, unless the wipers 293 and 313 are to remain in engagement with selected contacts. Upon this step of the carriage the switch S²² again closes its normal contact 306 and opens the contact 311 of switch S²³ and allows switch S²⁴ to assume its alternate position to close its alternate contact 316. The relay TWR² upon restoration, as before mentioned, causes the nose of its armature 43³ to engage a notch 50'. The arm 45' engaging the rail 64' causes the carriage SC' to be moved in an angular direction to place the wiper 297, etc., into engagement with the first set of contacts 301, etc. The closing of alternate contact 316 closes an energizing circuit for the magnet MM² traced from battery through the winding of MM², contact 286, conductor 285, alternate contact 316, conductor 324 to

ground at normal contact 325 of relay 321, causing the wipers to take another step into engagement with the contacts 301, 302, 303 and 304 which are the contacts of the wanted line, and when the wiper 300 engages the 70 grounded contact 304, an energizing circuit is established for relay TWR² traced from battery at contact 306, through conductor 307, winding of said relay TWR², conductor 308, wiper 300 contact 304, conductor 317, 75 contact 314 and wiper 313 to ground. The relay TWR² again attracts armature 43³, withdrawing its nose from the notch 50'. The wiper arm 45', when the wipers 297, 298, 299 and 300 are engaging the contacts 80 301, 302, 303 and 304 of the wanted line, is engaging a notch 65' in the rail 64' to hold the wipers in position. The motor magnet MM² continues stepping the carriage C' and the secondary carriage support as described 85 in connection with the selector, and when the switch makes its last step, switches S¹⁵ and S¹⁶ assume their alternate positions closing their respective alternate contacts 275 and 279, and the switch S²⁵ also assumes its alternate position closing its alternate contact 90 320. The closing of alternate contacts 275 and 279 establishes an energizing circuit for the relay 321 traced from battery through the winding of relay 321 conductor 322, alternate contact 279, normal contact 278, 95 contact 254, wiper 249, alternate contact 237, contact 59, wiper 53, alternate contact 80, ring contacts of the connected plug and jack CP and TJ, normal contact 212, through the windings of the polarized relay PO, alternate contact 207, normal contact 210, tip contacts of the connected plug CP and jack TJ, alternate contact 78, wiper 52, contact 100 58, alternate contact 234, wiper 246, contact 253, normal contact 277 to ground at alternate contact 275. The flow of battery through the relay PO is of such a direction that the relay PO attracts its armature to close its alternate contact 323 to light the 105 calling supervisory lamp CL and notify the operator that the called subscriber at substation H has not answered. The relay 321 upon energization opens normal contact 325 opening the circuit of motor magnet MM², 110 preventing further stepping of the switch. The contact S⁴⁰ is opened upon the twenty-second step of the magnet MM² before relay PR² de-energizes and contact S⁴⁰ remains open until the switch returns to normal. 120

Called line idle.

The private wiper 298 engaging private contact 302 of the idle line establishes an energizing circuit for the test relay STR and the cut-off relay CO' of the line circuit of the called line traced from battery through contact 326 of relay TWR², conductor 327, winding of the relay STR, conductor 328, wiper 298, contact 302, conductor 130

tor 329 through the winding of relay CO' to ground. The relay CO' upon energization removes the substation control of line relay LR', and the relay STR upon energizing opens its normal contact 330 disconnecting the busy back apparatus BB and also closes an energizing circuit for wiper control relay 500. The closure of alternate contact 331 of relay STR establishes an energizing circuit for the ringing relay RI traced from battery at alternate contact 332 of relay 321, over conductor 333, through the winding of relay RI, normal contact 334 of relay 335, conductor 336 to ground at alternate contact 331 of relay STR. The closure of alternate contact 337 of relay RI connects ringing current to the called substation H traced from the generator GE, through the interrupter I, conductor 338, contact 337, wiper 297, contact 301, through the call bell and condenser at the substation H back by way of contact 303, wiper 299, alternate contact 339, normal contact 340 of relay 335, through the winding of said relay 335 to battery. The call bell at the called substation H is thus intermittently rung and the said ringing current is disconnected on either a ringing or a silent period.

Should the subscriber at substation H answer during a silent period, the ground at the interrupter I would close a circuit for the relay 335 through the now closed switch hook contacts and should the subscriber answer during a ringing period, the combined generator and battery flow through the closed switch hook contacts and through the relay 335 will bring about its energization. The opening of normal contact 334 of relay 335 opens the circuit of relay RI to disconnect ringing current, and the closing of alternate contact 340 establishes a locking circuit for relay 335 traced from battery through the winding of said relay 335, its alternate contact 340 to ground at alternate contact 320. The closing of alternate contacts 341 and 342 of relay 335 establishes a circuit for the battery switching relay 277 traced from battery through the lower winding of relay 277 over conductor 344, through alternate contact 342, conductor 345, normal contact 339, wiper 299, contact 303 through the substation back over contact 301, wiper 297, normal contact 337, conductor 346, alternate contact 341, conductor 347 and through the upper winding of the relay 277 to ground. The closure of make before break contacts 348 and 349 causes a change in the direction of the battery flow through the polarized relay PO of the cord D. The circuit of the relay 321 now extends from battery through the winding of relay 321, conductor 322, contact 279, conductor 350, alternate contact 348, passing over the heavily marked conductors, and through relay PO back over the lower heavily

marked conductor, through alternate contact 349, conductor 351 to ground at alternate contact 275. The flow of current through relay PO is such that the contact 323 is opened to efface the signal CL, notifying the operator that the called subscriber at substation H has answered. The subscribers at substations A and H are now in conversational circuit, the talking circuit being traced over the heavily marked conductors.

Release.

Assuming now that the subscribers at the calling substation A and the called substation H have finished conversation, they replace their receivers upon their respective switch hooks and the replacing of the receiver by the subscriber at the calling substation A opens the energizing circuit for supervisory relay SR, and the relay SR restoring opens its alternate contact 203 and again closes its make before break contact 202, closing an energizing circuit for the supervisory lamp AL traced from battery through the supervisory lamp AL, contact 202, sleeve contacts of the connected plug AP and jack J through the winding of the cut-off relay CO to ground, thus lighting the supervisory lamp AL and notifying the operator that the calling subscriber at substation A has replaced his receiver. The called subscriber at the substation H replacing his receiver opens the energizing circuit for relay 277 at the switch-hook contacts, allowing the said relay to restore, and the closing of normal contacts 276 and 278 reverses the battery flow through the polarized relay PO and the flow is in such a direction that the armature 323 is attracted to close the circuit for the supervisory lamp CL from battery through the lamp CL to ground at alternate contact 323, thus lighting the said supervisory lamp CL and notifying the operator that the called subscriber at substation H has replaced his receiver.

The operator noting the two-lighted supervisory signals AL and CL knows that the respective subscribers at substations A and H have replaced their receivers, the said operator now withdraws the plugs AP and CP from the respective jacks J and TJ. The withdrawal of the plug AP opens the circuit for the cut-off relay CO and supervisory lamp AL, the said relay CO restoring to normal and the supervisory lamp AL is effaced. The withdrawal of the plug CP opens the circuit for the sleeve relay SL, the said relay SL restoring, and the polarized relay opens its alternate contact 323 to efface the supervisory signal CL. The apparatus of the cord circuit D is now at normal and available for establishing other connections.

The withdrawal of the plug CP from the

jack TJ opens the energizing circuit for the relay 321 of the connector G and the said relay 321 restoring, closes its normal contact 325 establishing an energizing circuit for the 5 motor magnet MM² traced from battery through the winding of the said magnet MM², through its normal contact 286, conductor 285, alternate contact 316 of switch S²⁴, and conductor 324 to ground at normal contact 325. It will be remembered that on the last step of the carriage C in a forward direction, it caused the rack 12' to be shifted into operative relation with the pawl 17' so that upon the operation of magnet MM² the pawl 17' engages a tooth of the rack 12' and moves the carriage C and secondary carriage SC' back one step. The motor magnet MM² is thus energized and de-energized due to the opening and closing 10 of its interrupter contact 286. The carriage C and secondary carriage SC' are stepped back to normal. The lug 67' engaging the arm 66² removes the wipers from engagement with the bank contacts and the 15 arm 45' from engagement with the rail 64'. The switch S⁴¹ closes its alternate contact 503 upon the first backward step of the carriage C' and this contact remains closed until the switch carriage C' reaches its normal 20 position. The wiper control relay 500 disconnects the line wipers from the switch while the switch is moving back to normal. The switch carriage upon reaching normal opens contact 503, thereby opening the circuit of magnet MM².

Upon the first step of the carriages in a rearward direction, switches S¹⁵ and S¹⁶ assume their normal position to close normal contact 275 and 279, as does switch S²⁵, 25 and the shifting of its contact 320 opens the circuit of relay 335 and as soon as wipers 298 and 300 disengage contacts 302 and 304 of the called line, relays STR and TWR² restore to normal. The switch S¹⁸ closes 30 its normal contact 287 upon the last step of the carriages back to normal closing an energizing circuit for the release relay RR' of the second selector F, as will presently be described. The return of the carriage C' 35 of the connector causes a lug, which is suitably secured to the carriage C', to engage the retaining pawls of the switches PSS² and PSS³ moving them out of engagement with the ratchet wheels to allow the wipers 293 and 313 of the respective switches PSS² and PSS³ to restore to normal by spring tension. The retaining pawls are held out of engagement with the ratchets until the switch carriage again moves off normal. 40 The switch upon reaching normal again closes contact S⁴⁰.

A circuit of release relay RR' of the second selector F is established, as above pointed out, over a circuit traced from ground at normal contact 287 of switch S¹⁸, 45

normal contact 281 of relay PR², conductor 360, contact 256, wiper 251, conductor 361, winding of relay RR' to battery and ground at alternate contact 246 of switch S¹⁰. The relay RR' upon energization closes its alternate contact 362 establishing an energizing circuit for the motor magnet MM', traced from battery through alternate contact 362, conductor 244, through the winding of magnet MM', normal contact 243 to ground at alternate contact 270 of switch S¹⁴. The magnet MM' is energized and immediately de-energized due to the opening of its alternate contact 243 and this actuation of MM moves the carriages back one step. Upon this first step, switch S¹⁰ assumes its normal position again closing its normal contact 246 so that when the wiper 251 disengages contact 256, the circuit of motor magnet MM' is maintained at normal contact 246. 50 The circuit of magnet MM' thus extends from battery at normal contact 246, over conductor 245, through the winding of magnet MM' and its normal contact 243 to ground at alternate contact 502 of switch S⁴³. The contact 502 is closed upon the first backward step of the switch and remains closed until the switch carriage reaches normal. The magnet MM' is thus energized and de-energized and for each de-energization of magnet MM', the carriages are stepped back step by step. Upon the first step of the carriage back to normal, the switches S⁷ and S⁸ assume their normal 55 positions to again close their normal contacts 234 and 237. The carriage when reaching normal engages the holding pawl of the switch PSS' moving it out of engagement with its associated ratchet to allow the wiper 265 to restore to normal, and restores off-normal contact 268 to normal. The switch carriage normally holds the holding pawl of the switch PSS² out of engagement with the ratchet of said switch. 60 The return of the carriage to normal again closes contact 258 of switch S¹¹ and opens contact 502 of switch S⁴³. The carriage returning to normal causes the upwardly extending lug 90' to engage the arm 66' to restore the switch carriage SC to normal. The switch F is now at normal and available 65 for use. The closure of normal contact 258 of switch S¹¹ establishes an energizing circuit for release relay RR of first selector E, traced from battery through alternate contact 79 of switch S², through the winding of relay RR, wiper 55, contact 61, normal contact 238 to ground at normal contact 258. The closing of alternate contact 370 of relay RR establishes an energizing circuit for magnet MM traced from battery through alternate contact 370, through the winding of magnet MM, normal contact 73, conductor 215 to ground at alternate contact 227 of switch S⁶. Upon the first rearward 70

step of the magnet MM, contact 501 is closed and remains closed until the switch carriages C and SC reach normal. The switches E and PSS are restored in a manner similar to that described in connection with switch F.

Referring to Fig. 9, it will be noted that switches S^{18} and S^{19} are end springs which are moved by the first step of the switch carriage from normal and are returned to normal by the return of the switch carriage to normal. Switches S^{15} , S^{16} and S^{22} are end springs operated on the twenty-second step of the switch carriage from normal and are restored by the first return step of the switch carriage. Switches S^{17} , S^{21} , S^{23} and S^{24} are controlled by wiper 520 and its co-operating contact strips. Switches S^{20} and S^{22} are controlled by wipers 521 and 522, respectively, and their co-operating contact strips.

Called line busy.

Should the called subscriber at substation H be busy, the connector bank private contact 302 will be at a battery potential and when the wiper 298 of the connector G engages the busy contact 302, no circuit is established for relay STR as both terminals of said relay STR are connected to battery, and the relay STR will fail to energize. The relay STR failing to energize, does not permit the wiper control relay 500 to energize and connect the calling line to the busy called line. The relay STR remaining at normal, connects the busy signal from busy back apparatus BB through its normal contact 330 over the vertical side of the line through alternate contacts 275, contact 276, contact 253, wiper 246; alternate contact 284, contact 58, wiper 52, alternate contact 78, tip contacts of the connected plug and jack CP and TJ, normal contact 210, alternate contact 207, tip contacts of the connected plug and jack AP and J through the calling substation A, back through the ring contacts of the connected plug and jack AP and J and through the lower winding of relay SR to ground. The calling subscriber at substation A hearing the busy signal replaces his receiver upon its switch hook, bringing about the de-energization of relay SR, which relay SR restores to close a circuit for supervisory lamp SS. The called line being busy, relay STR remains at normal and no circuit is established for relay RI and 335 and 227, as is readily understood from the previous description. Polarized relay PO is energized to close its contact 323 to light supervisory lamp SS' as previously described, and if the operator had her listening key thrown, she would also receive the busy signal. The operator noting the two lighted supervisory signals SS and SS' withdraws the plugs AP and CP from the

jacks J and TJ and the restoration of the switches E, F and G is the same as previously described.

While I have illustrated a preferred embodiment of my invention, it is apparent that it may be applied in various ways and also that many modifications and changes will readily suggest themselves to those skilled in the art. Therefore, I do not desire to be limited to the exact structure as shown, but aim to cover all that which comes within the spirit and scope of the appended claims.

What I claim as new and desire to secure by United States Letters Patent, is:

1. A two-dimension automatic switch provided with a bank of contacts divided into groups, a movable contact for cooperation with said bank of contacts, mechanism operatively associated with said movable contact for controlling the movement of said movable contact, and a driving magnet operatively associated with said mechanism for advancing said active contact to a group of contacts then to a contact in the elected group and for restoring said active contact to normal in a retrograde direction.

2. An automatic telephone system including contacts arranged in groups, a wiper adapted to engage all of said contacts, a ratchet for causing travel of said wiper to select a group, said ratchet also serving to continue travel of said wiper to select a contact of the selected group, means dependent upon the connections of the contacts encountered by said wiper for automatically causing the said continued travel of said wiper, a motor device for cooperation with said ratchet in advancing said wiper, another ratchet operatively associated with said wiper, said motor device also being operatively associated with said other ratchet to restore said wiper in a retrograde direction.

3. An automatic telephone system including subscribers' lines, circuit selecting switches at the exchange, means for interchangeably connecting said switches with calling lines, auxiliary selective switches one for each selecting switch, means for directly operating said auxiliary switches, said means including a relay controlled over a pair of talking conductors in series by a series of interruptions of the series circuit, means controlled by said auxiliary switches for automatically causing travel of said selecting switches to correspond to the extent of travel of their respective auxiliary switches, mechanism for thereafter continuing the travel of said selecting switches independently of said auxiliary switches, said last mechanism also including means for returning the circuit selecting switches to normal in a retrograde direction.

4. A semi-automatic telephone system

including link-circuits arranged in groups, a selective switch having multiple terminals of said link-circuits arranged in corresponding groups, group contacts at said switch 5 one for each group, movable contact members adapted to connect with said multiple terminals, apparatus, including a relay controlled over a pair of talking conductors in series by a series of interruptions of the 10 series circuit, for causing travel of said contact members to select a group, mechanism sensitive to the electrical condition of said group contacts determining the selection of the group, and means for thereafter continuing travel of said members to select 15 terminals of the selected group.

5. A telephone system including an automatic switch provided with a normally at rest contact maker, means for transmitting 20 current impulses over the two sides of a talking circuit in series from a control point, a control device individual to said switch set by said impulses in a position dependent upon the number of impulses transmitted, 25 and means for advancing said contact maker to a selective position dependent upon the position at which said control device is set, said means also being operative to restore 30 said contact maker in the same path in which said contact maker is advanced.

6. A selector comprising a normally at rest movable switch member, said movable switch member movable in a linear direction only, preselector mechanism individual 35 thereto, an electromagnetic step-by-step device responsive to selecting impulses transmitted over the two sides of a talking circuit in series by a number of interruptions of said series circuit for adjusting said 40 mechanism, a source of motive power for advancing said switch member, said mechanism being effective according to its selective adjustment for cutting off the application 45 of motive power from said switch member.

7. A selector comprising contacts and a normally at rest movable switch member, driving means for said switch member, said switch member being movable in a linear 50 direction only, an electromagnetically adjusted step-by-step device individual to said member and responsive to selecting impulses transmitted over the two sides of a talking 55 circuit in series from a control point by interrupting said series circuit a number of times, and means for causing said driving means to adjust and stop said switch member according to the adjustment of said device, said driving means also being operative 60 to restore said switch member to normal.

8. In a telephone system, a calling and a called subscriber's line, automatic switches for uniting said lines for conversation, groups of contacts for said switches, each 65 of said switches being provided with a shaft and contact wipers having primary movements to select a group of contacts and secondary movements to select a contact in a selected group of contacts, means including a single driving means for producing both movements and for restoring the switch shaft in a retrograde direction to normal.

9. A telephone system including a connecting circuit, a selector switch controlled over the two talking conductors of said circuit in series by a series of interruptions of said series circuit, a movable switch member for said selector switch, adjustable control mechanism, an electromagnetically controlled step-by-step device responsive to selective impulses for adjusting the said control mechanism, a source of motive power, means operated by said motive power to advance the said switch member in a linear direction only for both advancing and restoring said switch member, means controlled by said control mechanism according to its completed selective adjustment for disconnecting the motive power from said member, and a centralized source of current for furnishing all necessary operating current for said selector.

10. A semi-automatic telephone system including a selective switch, an auxiliary switch therefor, a contact wiper for said auxiliary switch, stationary contacts adapted to be engaged thereby, stationary contacts for said selective switch, connections between the contacts of said two switches, a contact wiper for said selective switch adapted to engage its said stationary contacts, a calling telephone line operatively connected with said switches, mechanism for transmitting directive currents over the two talking conductors of a circuit in series by interrupting said series circuit a number of times, apparatus responsive to said currents for causing travel of the contact wiper of said auxiliary switch, and mechanism including said stationary contacts of both switches for automatically causing travel of said contact wiper of said selective switch corresponding to the travel of the auxiliary switch.

11. A semi-automatic telephone system including trunk circuits having multiple terminals arranged in groups, group contacts one for each group, a selective switch, a group private wiper therefor adapted to move over said group contacts, an individual private wiper therefor adapted to engage the multiple terminals of all said groups, mechanism for altering the normal electrical conditions of said group contacts, mechanism for altering the normal electrical conditions of said multiple terminals, and means controlled over the two talking conductors of a circuit in series by interrupting the series circuit a series of times for operating and releasing said selective switch.

12. An automatic telephone system including trunk circuits having multiple terminals arranged in groups, group contacts one for each group, a selective switch, a group private wiper therefor adapted to move over said group contacts, an individual private wiper therefor adapted to engage the multiple terminals of all said groups, pawl and ratchet mechanism for said switch, mechanism for altering the normal electrical conditions of said group contacts, mechanism for altering the normal electrical conditions of said multiple terminals, an electromagnet for controlling the operation of said switch, a circuit for said electromagnet including said group private wiper for determining operation of said switch to select a group, and a motor driving magnet operatively associated with said pawl and ratchet mechanism for both advancing and returning in a retrograde direction said private wipers to normal. 10
13. An automatic telephone system including trunk circuits having terminals arranged in groups, group contacts one for each group, a selective switch, pawl and ratchet mechanism for said switch, a group private wiper therefor adapted to move over said group contacts, an individual private wiper therefor adapted to engage the multiple terminals of all said groups, auxiliary switch mechanism for altering the normal electrical conditions of pre-determined group contacts, mechanism for altering the normal electrical conditions of said multiple terminals, and a motor driving magnet operatively associated with said pawl and ratchet mechanism for both advancing and returning in a retrograde direction said private wipers to normal. 20
14. An automatic telephone system including trunk circuits having multiple terminals arranged in groups, group contacts one for each group, a selective switch controlled over the two talking conductors of a circuit in series by a series of interruptions of the series circuit, pawl and ratchet mechanism for said selective switch, a group private wiper therefor adapted to move over said group contacts, an individual private wiper therefor adapted to engage the multiple terminals of all said groups, auxiliary switch mechanism for altering the normal electrical conditions of pre-determined group contacts, mechanism for altering the normal electrical conditions of said multiple terminals, an electromagnet for controlling the operation of said switch, a circuit for said electromagnet including said group private wiper for determining operation of said switch to select a group, and a motor driving magnet operatively associated with said pawl and ratchet mechanism for both advancing and returning in a retrograde direction said private wipers. 30
15. An automatic telephone system including a subscriber's line, a selective switch, multiple terminals associated therewith arranged in groups, controlling mechanism for said switch operatively related to said line, including an auxiliary switch, means for transmitting directive currents over the two talking conductors of a circuit in series by interrupting the series circuit a number of times to operate said auxiliary switch to determine selection of a group, means for automatically causing travel of said selective switch determined by the travel of said auxiliary switch to place said selective switch in operative relation with the selected group, and means including a magnet for advancing and returning in a retrograde direction said selective switch. 70
16. An automatic telephone exchange including a selective switch, an auxiliary switch therefor, magnets for causing travel of said switches, one for each switch, a subscriber's line operatively connected with said switches, means for transmitting directive currents over the two talking conductors of a circuit in series by a series of interruptions of the series circuit, mechanism for operating the magnet of said auxiliary switch responsive to a first set of directive impulses transmitted, apparatus automatically responsive to the operation of said magnet for actuating the magnet of said selective switch, means for thereafter rendering effective the magnet of said selective switch to respond to a second set of directive impulses independently of said auxiliary switch, and means controlled by the magnet of said selective switch for restoring the same in a retrograde direction. 80
17. A telephone system including multiple contacts arranged in groups, an electromagnetically driven selective switch having two movements of travel, means for said switch for effecting said two movements, means for transmitting directive currents over the two talking conductors of a trunk circuit in series by a series of interruptions of the series circuit to select a group of contacts, means for setting up an independently progressive travel of said switch to automatically select definite contacts of a group, said electromagnetically driven switch being adapted to be advanced and restored by a single driving magnet operatively associated with said first means. 90
18. A telephone system including multiple contacts arranged in groups, a selective switch, pawl and ratchet mechanism for said switch, means for setting up an independent progressive travel of said switch for selecting a group of multiple contacts, means for setting up an independent progressive travel of said switch to automatically select definite contacts of a selected group, and a single electromagnetic driving means asso- 100

- ciated with said pawl and ratchet mechanism for both advancing the said switch and for restoring said switch in a retrograde direction.
- 5 19. A telephone system comprising an automatic switch, means for transmitting current impulses from a control point over the two talking conductors of a trunk circuit in series by interrupting the series circuit a number of times, a starting device individual to said switch set by said impulses in a position dependent upon the number of impulses transmitted, and electromagnetic driving means for advancing said switch to 10 a position dependent upon the position at which said starting device is set and for restoring said switch from said position in a retrograde direction.
- 10 20. A telephone system comprising automatic switches for interconnecting telephone lines, starting devices for said switches, each of said devices adapted to be set in any one of a plurality of positions, means for advancing said switches to positions dependent upon 15 the positions at which the said starting devices are set, and means including a driving electromagnet for each of said switches for advancing and restoring the same in the same paths in which said switches are advanced.
- 20 21. A telephone system comprising an automatic switch capable of primary and secondary adjustments, means for transmitting current impulses from a control point over the two talking conductors of a trunk circuit in series by interrupting the series circuit a number of times, a starting device for said switch set by said impulses in a position dependent upon the number of impulses transmitted, means actuated thereby to adjust said switch to a primary position dependent upon the position at which said starting device is set, means for giving said switch its secondary adjustment, and a common driving 25 and restoring magnet for said switch, said switch being controlled so that it restores in the same path of travel in which said switch is advanced.
- 25 22. A telephone system comprising an automatic switch, means for transmitting current impulses from a control point over the two talking conductors of a trunk circuit in series by interrupting the series circuit a number of times, a starting device for said switch having a member set by said impulses in a position dependent upon the number of impulses transmitted, said switch being adapted to travel to positions corresponding to positions of the starting device, means for starting the advance of said switch upon the initial movement of said member and discontinuing it when it has traveled according to the adjusted position of the starting device, and a common driving and restoring magnet for said switch,
- 30 said switch being controlled so that it restores in the same path of travel in which said switch is advanced.
- 35 23. A selector switch comprising contacts arranged in groups, an auxiliary switch for said selector having contacts corresponding to said groups, said auxiliary switch being adapted to be electromagnetically operated responsive to impulses transmitted over the two talking conductors of a trunk circuit in series by a series of interruptions of the series circuit to select any of said groups, wipers common to and adapted for cooperation with each of said groups, means for automatically moving said wipers to the selected group, and a common driving and restoring magnet for said selector switch, said switch being controlled so that it restores in the same path of travel in which said switch is advanced.
- 40 24. A selector switch comprising contacts arranged in groups, an auxiliary switch for said selector having contacts corresponding to said groups and connected therewith, said auxiliary switch being adapted to be operated responsive to impulses transmitted over the two conductors of a trunk circuit in series by a series of interruptions of the series circuit to select any of its contacts and thus the corresponding group, a set of wipers adapted for cooperation with all of the contacts of said groups, automatic means for moving said wipers to the selected group, and a common driving and restoring magnet for said selector switch, said switch being controlled so that it restores in the same path of travel in which said switch is advanced.
- 45 25. A telephone exchange system comprising subscribers' lines and automatic switches having multiple contacts arranged in groups and link-circuits for uniting calling and called lines into conversational circuits, said switches each provided with a shaft having contact wipers, said shaft having primary movements to select a group of contacts and secondary movements to select a contact in a group, and means for said switch including a single driving means for producing both movements, and means also including said single driving means for restoring the switch in the same path in which said shaft is advanced.
- 50 26. A selector comprising a movable switch member, electromagnetically driven control mechanism individual to the selector, an electromagnetic step-by-step device responsive to selective impulses, transmitted over the two talking conductors of a trunk circuit in series by interrupting the series circuit a series of times, for adjusting said control mechanism, a source of motive power, means operated by the said power to advance the said switch member, means controlled by said control mechanism ad-

cording to its completed selective adjustment, for rendering the motive power ineffective to further advance the said switch member, and means including said motor power for restoring said switch member to normal in a retrograde direction.

27. A telephone system including an automatic selector switch, an electromagnetically driven control device individual to the said switch and adapted to be set in any one of a plurality of positions, a driving magnet, and means including said driving magnet for advancing said switch to a selective position dependent upon the position at which said control device is set, and means including said driving magnet for restoring the said switch in a retrograde direction in the same path in which said switch is advanced.

28. An automatic telephone system including terminal contacts arranged in groups, a selective switch controlled over the two talking conductors of a trunk circuit in series having movable members for engaging said contacts and adapted to operate when the series circuit is interrupted, group contacts at said switch, one for each group, means for altering the normal electrical condition of a group contact, means for altering the normal electrical condition of terminal contacts, an electromagnet sensitive to the electrical condition of said group contacts for controlling travel of said members to select a group, means for continuing travel of said members to select contacts of a selected group, and a magnet for

both advancing and restoring said movable members, said movable members restoring in the same path of travel in which they are advanced.

29. A selector including contacts arranged in groups, movable members to make connection with said contacts, said members having a definite normal position and movable in a linear direction only, mechanism for adjusting said members to select a group, and circuit connections thereupon effective whereby said mechanism also serves to continue travel of said members, to select contacts of the group, and, when disconnection is desired, to restore said members to normal by returning them in the opposite direction, circuit connections including the two talking conductors of a trunk circuit in series for controlling said mechanism when the series circuit is interrupted a number of times, a calling device, and means for interrupting said circuit.

30. A telephone system including an automatic switch, a movable element for said switch movable in a linear direction only, contact makers for said switch movable both in a linear and in an angular direction, and means including a motor magnet controlled by said movable element for moving said contact makers step-by-step in both of said directions and for restoring the same.

Signed by me at Chicago, in the county of Cook, and State of Illinois this 2nd day of January, 1919.

LEROY D. KELLOGG.
